UNITED STATES PATENT OFFICE.

BRUTUS I. H. MITCHELL, OF ONAWA, IOWA.

TUG ATTACHMENT.

SPECIFICATION forming part of Letters Patent No. 739,502, dated September 22, 1903.

Application filed November 7, 1902. Serial No. 130,449. (No model.)

To all whom it may concern:

Be it known that I, BRUTUS I. H. MITCHELL, a citizen of the United States, residing at Onawa, in the county of Monona and State of Iowa, have invented certain new and useful Improvements in Tug Attachments; and I do hereby declare the following to be a full, clear, and exact description of the invention, such as will enable others skilled in the art to which it appertains to make and use the same.

My invention has relation to harness construction and appertains more particularly to a tug attachment which will adapt the tug of a working harness for use upon a buggy or carriage without the necessity of employing the usual metallic terminal or cockeye to connect with the end of the swingletree of the buggy.

The object of my invention, among others, is to enable a set of working harness to be readily adapted for use in connection with a buggy or carriage, so that there will be no rattle or undue wear upon the swingletree.

Other objects and advantages will be made clearly apparent from the following specification, considered in connection with the accompanying drawings, which are made a part of this application, and in which—

Figure 1 shows a side elevation of my invention complete. Fig. 2 shows an edge view of Fig. 1. Fig. 3 shows a central longitudinal section of Fig. 1. Fig. 4 shows another form of construction. Fig. 5 is an edge view of Fig. 4. Fig. 6 is a longitudinal central section of Fig. 4, while Fig. 7 is a transverse section of Fig. 4 on line *x* *x*.

Briefly stated, my invention consists in providing an eye-section of leather or the like having a suitable aperture, as is common, to receive the end of a wooden swingletree of a buggy, said end section being provided with a suitable clamp by which it may be disposed in separable union with the end link of a trace-chain or with a cockeye-terminal usually found on working harness.

The various elements of my invention and coöperating features will be designated by numerals, the same numeral referring to a similar part throughout the several views.

Referring to the numerals on the drawings, 1 indicates the end of a tug of a working harness, which is provided at its end with a cock-

eye 2, pivotally secured there in the usual manner, as by the bolt 3.

In carrying out my invention I provide the member 4, having an aperture 5 to receive the end of a swingletree of a buggy or carriage, and to the forward end of the member 4 I pivotally connect a clip having the forwardly-extending arms 6, each arm having an aperture 60 in its end disposed in registration with each other to receive the bolt 7, which passes through the tubular hinge 8 of the metallic jaws 9, said jaws and hinged member 8 being entirely inclosed by a covering of leather 10, 65 said parts being permanently united together in any preferred way, as by the rivets 11 or the equivalent thereof. The forward ends of the jaws being thus left to open freely, are adapted to receive the cockeye 2, said cockeye 70 being held therein by the post 12, which carries the spring-controlled button 13, which is preferably oval or oblong in form, as shown in Fig. 1. The button 13 is thus rotatably mounted in position, and being oblong in form 75 is adapted to pass through the elongated aperture 14, formed in a contiguous part of the opposite jaw, and it is obvious that since the aperture 14, is longitudinally disposed with respect to the jaw the button 13 is adapted to 80 extend entirely through the same, when it may be turned in its seat, and thus disposed transversely across the jaw, and thereby secure the same, whereby the cockeye will be locked securely in place between the jaws, 85 causing the strain of the cockeye to be disposed upon the post 12, and thereby dispose the member 4 as a practical continuation of the tug 1, and thus enabling the tug of a working harness to be fitted for use as a harness 90 for a buggy or carriage.

The edges 25 of the jaws 9 are bent at right angles to the body portions thereof, so that when the said jaws are in their closed position said edges will be brought together, and 95 thus form a housing, whereby the free end of the cockeye 2 will be incased and held against lateral or pivotal movement, and at the same time it will be covered up and removed from sight, practically presenting a continuous 100 leather tug.

In some instances the securing device 13 may be omitted and replaced by surrounding the jaws upon three sides with the member

15, as shown in Fig. 7, said member being secured to the lower jaw 16, as by the rivets 17 or the equivalent thereof. The casing or member 15 being thus disposed, so that it 5 will inclose three sides of the two jaws when brought together, is formed upon each of its edges with the outwardly-directed lip 17^a, adapted to be engaged by the curved lips 18 of the lid-section 19, which latter is adapted 10 to be slid in place, so as to cause the entire four sides of the jaws to be inclosed.

When it is desired to open the jaws illustrated in Figs. 4, 5, 6, and 7, all that is necessary is to slide the lid 19 out of engagement 15 with the lips 17^a, and when said lid 19 is thus removed the jaws may be freely opened and the cockeye, as indicated by the numeral 20, slipped in place over the post 21, which is carried by the jaw 16. The post 21 is adapted 20 to extend upward through an aperture provided in the upper jaw 22, so as to insure that said post will be reliably reinforced and sustained in its position, and thereby held against the strain placed upon it by the cockeye. 25 It is therefore obvious that the clamping-jaws may be variously secured together in engagement with the cockeye, and I therefore reserve the right to employ either form of securing device, as illustrated by the rotatable button 13 or the housing or casing 30 15 and its coöperating lid, reserving the right to use either form in practice which I may find most desirable to meet the varying requirements for such an appliance.

35 In opening the jaws illustrated in Figs. 1, 2, and 3 all that is necessary to be done is to turn the rotatable button so that it will register with the longitudinally-disposed opening 14, when the jaws may be freely separated, 40 inasmuch as the button 13 will pass freely through the opening 14. When, however, it is desired to lock the jaws together, the button is extended through the opening 14 and then turned so as to be disposed transversely 45 with respect to the jaws, thereby holding the same securely in place, it being understood that the securing-spring 23 will be so disposed as to hold said button in an adjusted

position. Inasmuch as the housing 15 is permanently secured to one of the jaws, it cannot become casually displaced or lost, and when the lid-section 19 is removed the jaws are left free to be separated for the removal of the cockeye or for securing it in place between the jaws. 50

55 While I have described the preferred construction and combination of parts deemed necessary in carrying out my invention, I wish to comprehend all substantial equivalents and substitutes that may be considered as falling fairly within the scope of my invention. 60

Having thus fully described my invention, what I claim as new, and desire to secure by Letters Patent, is—

65 1. The herein-described tug attachment comprising the combination with a tug having an eye or ring, of a member 4 having a suitable aperture to receive a swingletree; a clip carried by the forward end of said member 4; clamping-jaws hinged to said clip and having their edges bent inwardly at right angles to their body portions; a covering for said jaws; a hollow post formed integral with one of the said jaws; a button having a stem 70 carried by said post, the coöperating jaw having an elongated transverse aperture adapted to receive said button and a spring surrounding said stem and arranged to keep the button in contact with said jaw, substantially as 75 specified and for the purpose set forth.

2. In a tug attachment, a member 4 having a suitable aperture to receive a swingletree; a clip carried at one end of said member 4; clamping-jaws hinged to said clip, said jaws 80 having their edges bent inwardly at right angles to their body portions and suitable means for locking said jaws together as and for the purpose set forth.

85 In testimony whereof I affix my signature in presence of two witnesses.

BRUTUS I. H. MITCHELL.
